UNITED STATES PATENT OFFICE.

EDWARD BURGER, OF KOKOMO, INDIANA.

HEATER ATTACHMENT.

SPECIFICATION forming part of Letters Patent No. 739,384, dated September 22, 1903.

Application filed February 13, 1903. Serial No. 143,242. (No model.)

To all whom it may concern:

Be it known that I, EDWARD BURGER, a citizen of the United States, residing at Kokomo, in the county of Howard and State of Indiana, 55
have invented a new and useful Heater Attachment, of which the following is a specification.

My invention relates to attachments for stoves and similar apparatus, and has for its 10 object the effecting of more perfect combustion therein.

In the accompanying drawings, Figure 1 is a vertical sectional view of a stove having my 15 invention applied thereto. Fig. 2 is a perspective view of a device, showing the embodiment of my invention in its preferred form.

Similar characters indicate like parts throughout both figures of the drawings.

Some form of heating apparatus, here shown 20 as the cylinder stove, is designated by the letter S, provided with the usual funnel 10, leading from the top thereof, and with a lower draft 11 and funnel-damper 12. Within the 25 stove, preferably fitting closely against the casing, is the air-heating portion H of my improved attachment. This may consist of an upper section 13, which may be tubular in cross-section, formed or bent to a contour to fit the particular stoves in which it is to be used. It is shown as non-continuous or with a part removed to allow for the stove-door, but with the ends closed. Nipples 14, here 30 shown as three in number, depend from this section, and over each of these nipples may be slipped a vertical pipe 15, fitting at their lower ends over nipples 16, projecting upward from a lower section 17. This section 17 is 35 preferably circular in general contour of the

open angular cross-section illustrated and situated with the edges of its inner and lower faces in frictional contact with the interior of the casing and said lower face just above the surface of the grate. In this bottom face is 40 provided a suitable number of openings 18.

The sections 13 and 17 may be formed of either sheet or cast metal, but preferably the latter. They may be retained in position by the frictional contact of the outer edges of 45 the section 17 with the interior of the stove and by the outward spring of the open or parti-circular section 13. As an additional

support the section 13 is shown as seated in a groove in the stove-casing and the section 17 with its upper edge resting upon a shoulder projecting therefrom.

From the section 13, preferably at a point beneath the funnel, extends a nipple 19, over which is slipped an induction-pipe 20, passing up into the funnel and being provided 55 with an elbow at 21 to enable it to pass through the side of the funnel to give an opening 22 into the exterior air. In this pipe 20 is shown a damper 23 to govern the quantity of air admitted.

To assemble the apparatus, either the lower or upper section is first put in place through the top or bottom of the casing, respectively, as is most convenient, the pipes 15 are placed over the nipples, and the companion section 70 70 is inserted and their nipples brought into co-action with the pipes. Then the pipe 20 is put in position and the funnel with the elbow adjusted.

When combustion is taking place in the 75 stove, the upward draft therethrough, controlled in the usual manner by the stove-dampers, draws fresh air through the opening 22, from which it passes through the pipe 20 into the section 13, down the pipes 15, and into 80 the section 17, becoming progressively more and more heated until it is discharged at a very high temperature through the openings 18 under the grate. There it mingle, passes 85 upward through the burning fuel and furnishes abundance of oxygen in the proper condition to insure the perfect combustion thereof and of the particles of carbon, which, together therewith, constitute the smoke. This in turn serves to draw in and heat the 90 descending air in the sections and pipe.

Having thus described the invention, what I claim is—

1. In a device of the class described, the combination with a cylindrical heater-casing 95 having an ash-pit, a grate and an annular offset, of an air-chamber, triangular in cross-section, the outer wall of said chamber being formed by the stove-casing and the inner and lower walls by inclined and horizontal members, the latter being supported upon the 100 grate and the former being provided with a supporting-flange resting upon the shoulder or offset.

2. In a device of the class described, the combination with a cylindrical stove-casing having an ash-pit, a grate, and an annular shoulder or offset, of an annular downwardly-converging member supported upon the shoulder or offset, an annular horizontally-disposed member connected with the lower edge of the downwardly-converging member and coöperating therewith and with the stove-casing to form an annular air-heating chamber, nipples extending upwardly from the downwardly-converging wall of said chamber, and connecting means for the conveyance of air downwardly through the stove-casing to said annular air-chamber, the bottom member of the latter being provided with openings for the

passage of the heated air into the ash-pit and thence upwardly from the grate to support combustion.

3. The combination with a casing, of a bent non-continuous air-heating section having a space between its ends and possessing some spring to engage the casing.

In testimony that I claim the foregoing as my own I have hereto affixed my signature in the presence of two witnesses.

EDWARD X BURGER.
